FURNACE STOKER

Joseph S. Bennett, Merion, Pa., assignor to American Engineering Company, Philadelphia, Pa., a corporation of Pennsylvania

Application October 23, 1934, Serial No. 749,539

15 Claims. (Cl. 122—4)

This invention relates to stoker furnaces, and more particularly to stokers having fluid cooling means associated therewith for preventing clogging of the tuyère openings by slag and clinker formations. The ash content of certain types of coals, it has been found, not only fuses at a comparatively low temperature, but forms an impervious mass when cooled which clogs the air openings of the grates as well as impairs the operation of the stoker as a whole. In many cases it is necessary to extinguish the fire at frequent intervals so that the slag and clinker masses adhering to the grates may be removed.

One object of the present invention is to provide means for preventing such damage to the grates and to insure efficient burning of all fuels.

Another object is to provide in stoker furnaces of the character set forth means for elevating the zone of combustion so that incandescent fuel and molten ash will be out of contact with the furnace grates.

A further object is to interpose fluid cooled means between the grates and the incandescent portion of the fuel bed which acts as a screen for cooling any slag flowing through the fuel mass, before it comes in contact with the grates.

Another object is to provide over the tuyère rows in an underfeed stoker a series of fluid conducting tubes which raises the zone of combustion above the tuyères and chills any slag or clinker formations before they come in contact with the tuyères, thus minimizing the adherence thereto of such slag or clinker formations.

A still further object is to provide in an underfeed stoker a plurality of fluid conducting tubes over the tuyère rows thereof, and also over the extension grates to prevent the adherence of clinkers to the various grates of the stoker, and to insure efficient combustion of all types of fuel thereon.

A further object is to provide an improved furnace tuyère having recesses provided therein for receiving a series of fluid conducting tubes.

Other and further objects will become apparent as the description of the invention progresses.

Of the drawings:

Fig. 1 is a longitudinal sectional view taken through a stoker furnace showing fluid conducting tubes arranged in cooling relation with the tuyères, dead plates and ash pocket walls.

Fig. 2 is a plan view of the stoker shown in Fig. 1 with parts broken away to show the arrangement of certain of the tubes and headers of the fluid cooling system associated therewith.

Fig. 3 is a sectional view taken substantially along line 3—3 of Fig. 1.

Fig. 4 is a modification of the structure shown in Fig. 3 showing the tubes resting upon the upper surface of the tuyère blocks.

Fig. 5 is a further modification of the structure shown in Fig. 3 showing the tubes arranged in spaced relation with respect to the top of the tuyère blocks.

Fig. 6 is a plan view of one of the tuyère blocks provided on the stoker.

Fig. 7 is a sectional side view of the tuyère block shown in Fig. 6.

Referring to the drawings, the numeral 1 designates a furnace having provided therein an underfeed stoker 2, comprising alternately disposed retorts 3 and tuyère rows 4. Fuel is fed into the retorts 3 from hoppers 5 by any suitable feeding mechanism 6. Fuel entering the retorts 3 is underfed over the length thereof by a series of pushers 8 to an ash pocket 53 disposed at the rearwardly disposed end of the stoker. Draft air is supplied to the furnace from a plenum chamber 44 disposed beneath the stoker 2. Plenum chamber 44 may be connected to any source of air supply by means of a communicating passage 47. The side walls of the furnace adjacent the stoker 2 have each provided therein a fluid cooled panel 18 comprising front and rear headers 19 and 20 respectively, connected by a series of fluid conducting tubes 21. A downcomer 22 connects header 20 with the boiler 16, while header 19 is connected to the boiler by a riser 23. A series of fluid conducting tubes 25 is mounted on the tuyère blocks of each of the tuyère rows 4. The lower ends of tubes 25 are bent downwardly over the rear end of the stoker and the substantially vertical extensions 54' thereof form a portion of the front wall 54 of the ash pocket 53. The lower ends of tubes 25 then extend forwardly and terminate in a header 55 mounted in any suitable manner beneath the stoker. The tubes 25 are connected at their upper ends to header 26, which in turn may be connected to the boiler 16 by any suitable riser connection 26A. A second series of tubes 56 extend rearwardly from a header 57 suitably mounted beneath the stoker, and the substantially horizontal portions thereof are mounted in close juxtaposition with the lower surfaces of the dead plates 58 provided at the lower ends of the retorts of the stoker. The tubes 56 then extend downwardly and occupy the spaces between the vertically disposed portions 54' of tubes 25 and form therewith the exposed portion of the front wall 54 of the ash pocket. The lower ends of

tubes 56 are connected to header 26, which in turn may be connected to the boiler 16 by any suitable riser connection 26A. A second series of tubes 56 extend rearwardly from a header 57 suitably mounted beneath the stoker, and the substantially horizontal portions thereof are mounted in close juxtaposition with the lower surfaces of the dead plates 58 provided at the lower ends of the retorts of the stoker. The tubes 56 then extend downwardly and occupy the spaces between the vertically disposed portions 54' of tubes 25 and form therewith the exposed portion of the front wall 54 of the ash pocket. The lower ends of

tubes 56 also extend forwardly and terminate in header 55. Header 57 may also be connected to the boiler by any suitable riser connection 57'. The rear wall 59 of ash pocket 53 also comprises

5 a series of fluid conducting tubes 60 mounted in upper and lower headers 61 and 62 respectively. It therefore is seen that the entire area of the furnace which is exposed to the intense heat of the incandescent fuel is effectively cooled. In 10 this construction a booster pump 101 may also be employed to assist the natural circulation in the system, said pump being connected to the boiler 16 by downcomer connection 102.

When no booster pump is employed in the 15 system the header 57 connected to the forwardly disposed ends of tubes 56 may be elevated so as to assume a position in alignment with or slightly above the horizontally disposed portions of said tubes.

20 Under certain conditions it may be desirable to partially imbed the tubes 25 in the tuyères 4, as indicated in Fig. 3. To this end the nose portion of each tuyère block 4 is provided with a series of depressions 67, which in assembly receive the 25 tubes 25. Tuyères blocks 4 are provided with the usual projections or ribs 68 defining passages for draft air. When the tubes are seated in intimate contact with the tuyère blocks, as illustrated in Fig. 3, the blocks are effectively cooled and thus 30 capable of withstanding the severe conditions of furnace operation. The draft air flowing through the tuyère blocks also produces a cooling effect thereon. However, under certain conditions, it has been found desirable to simply rest the tubes 35 25 upon the upper surfaces of the tuyères as shown in Fig. 4. It has also been found desirable in certain installations to space the tubes 25 from the tuyère blocks 4, as shown in Fig. 5. Whether the tubes are to be placed in intimate contact 40 with the tuyère blocks as shown in Fig. 3, or arranged in the manner shown in Figs. 4 and 5, depends upon the conditions of operation of the furnace and upon the types of fuel to be burned therein. The tubes 25 arranged in the manner 45 shown in Figs. 3, 4 and 5 act as a cooling screen and chill any molten ash flowing toward the tuyères or extension grates, thus causing the same to partially solidify before coming in contact with the tuyères or grates. The slag or clinker thus chilled will not adhere to the tuyère blocks, and accordingly will be carried down the fuel bed by the general movement of the fuel 50 to the ash pit and dumped therein.

The various constructions herein shown and 55 described not only lower the maintenance cost of stokers, but permit furnaces to operate for long periods of time without interruption. These constructions are especially desirable when the fuels burned are of the type wherein the ash content 60 thereof fuses at low temperatures. This molten ash has a tendency to clog the tuyère openings, and thus prevents the proper amount of air from entering the fuel bed. This also causes considerable damage to the grates with the result that 65 the maintenance cost is not only high, but a considerable loss is experienced in taking the boilers off the line to make the necessary repairs. The various constructions herein shown have largely 70 eliminated these undesirable conditions and have also increased the efficiency of the units as well.

While the invention is shown applied to stokers of the underfeed type, it is believed to be apparent that it is equally adaptable for use in other types of stokers as well. The invention 75 therefore is not to be limited to the embodiments

herein shown since it may be embodied in other forms, all coming within the scope of claims which follow.

What is claimed is:

1. In an underfeed stoker, comprising in combination, alternately disposed tuyère rows and retorts, dead plates disposed near one end of said stoker, a series of fluid conducting tubes mounted over each of said tuyère rows forming a screen for chilling any molten ash passing through the fuel bed toward said tuyères, and a second series of tubes disposed in cooling relation to said dead plates. 5

2. In an underfeed stoker, comprising in combination, alternately disposed tuyère rows and retorts, an ash pocket disposed at one end of said stoker having a front wall, dead plates disposed at the bottom of said retorts, a series of fluid conducting tubes mounted over each of said tuyère rows forming a screen for chilling any molten ash 10 passing through the fuel bed toward said tuyères, said tubes extending downwardly and forming a portion of the front wall of said ash pocket and terminating in a header, a second series of tubes disposed beneath said dead plates and in cooling 15 relation therewith, said last mentioned tubes also extending downwardly over the said front wall and in the same plane with said first mentioned tubes and terminating in said header, a boiler, means connecting said tubes and header to said 20 boiler, and a booster pump for feeding fluid under pressure from said boiler to said header. 25

3. In an underfeed stoker, comprising in combination alternately disposed retorts and tuyère rows, dead plates disposed at the lower end of said retorts, an ash pocket disposed at one end of said stoker having a front wall, a series of fluid conducting tubes mounted over each of said tuyère rows, said tubes extending downwardly and forming a portion of the front wall of said 35 ash pocket, a second series of tubes disposed beneath said dead plates in cooling relation therewith, and headers connected to the terminal ends of said tubes. 40

4. In an underfeed stoker, comprising in combination alternately disposed tuyère rows and retorts, an ash pocket disposed at one end of said stoker having a front wall, dead plates disposed at the bottoms of said retorts, a series of fluid conducting tubes mounted over each of said tuyère rows forming a screen for chilling any molten ash 50 passing through the fuel toward said tuyères, said tubes extending downwardly and forming a portion of the front wall of said ash pocket, a second series of tubes disposed beneath 55 said dead plates and in cooling relation therewith, said last mentioned tubes also extending downwardly over said front wall and lying in the same plane with said first mentioned tubes, and headers for the terminal ends of said tubes. 60

5. In an underfeed stoker, comprising in combination alternately disposed tuyère rows and retorts, an ash pocket disposed at one end of said stoker having a front wall, dead plates disposed at the bottom of said retorts, a series of fluid conducting tubes mounted over each of said tuyère rows forming a screen for chilling any molten ash passing through the fuel toward said tuyères, said tubes extending downwardly and forming a 70 portion of the front wall of said ash pocket, a second series of tubes disposed beneath said dead plates and in cooling relation therewith, said last mentioned tubes also extending downwardly over said front wall and lying in the same plane with 75

- said first mentioned tubes, a boiler, and means connecting said tubes to said boiler.
6. In an underfeed stoker, comprising alternately disposed retorts and tuyère rows, fuel supporting means disposed at the lower ends of said retorts and lying between said tuyère rows, one or more fluid conducting tubes mounted in cooling relation with the tuyères of each of said rows, and one or more fluid conducting tubes disposed in cooling relation with said fuel supporting means.
7. In an underfeed stoker, comprising alternately disposed retorts and tuyère rows, of dead plates disposed near one end of said stoker, one or more fluid conducting tubes mounted in cooling relation with the tuyères of each of said rows, and one or more fluid conducting tubes disposed in cooling relation with said dead plates.
8. In an underfeed stoker, comprising alternately disposed retorts and tuyère rows, of fuel supporting means disposed at the lower ends of said retorts and lying between said tuyère rows, an ash pocket disposed at one end of said stoker having a front wall, one or more fluid conducting tubes mounted in cooling relation with the tuyères of each of said rows, said tubes extending downwardly and forming a portion of the front wall of said ash pocket, one or more fluid conducting tubes disposed in cooling relation with said fuel supporting means, and means for supplying fluid to said tubes.
9. In an underfeed stoker, comprising in combination alternately disposed retorts and tuyère rows, dead plates disposed at the lower end of said retorts, an ash pocket disposed at one end of said stoker having a front wall, one or more fluid conducting tubes mounted in cooling relation with the tuyères of each of said rows, said tubes extending downwardly and forming a portion of the front wall of said ash pocket, one or more fluid conducting tubes disposed in cooling relation with said dead plates, and means for supplying fluid to all of said tubes.
10. In an underfeed stoker, comprising alternately disposed retorts and tuyère rows, of fuel supporting means disposed at the lower ends of said retorts and lying between said tuyère rows, an ash pocket disposed at one end of said stoker having a front wall, one or more fluid conducting tubes mounted in cooling relation with the tuyères of each of said rows, said tubes extending downwardly and forming a portion of the front wall of said ash pocket, one or more fluid conducting tubes disposed in cooling relation with said fuel supporting means, a boiler, and means operatively connecting said tubes to said boiler.
11. In an underfeed stoker, comprising in combination alternately disposed retorts and tuyère rows, dead plates disposed at the lower end of said retorts, an ash pocket disposed at one end of said stoker having a front wall, one or more fluid conducting tubes mounted in cooling relation with the tuyères of each of said rows, said tubes extending downwardly and forming a portion of the front wall of said ash pocket, one or more fluid conducting tubes disposed in cooling relation with said fuel supporting means, a boiler, and means operatively connecting said tubes to said boiler.
12. In an underfeed stoker, comprising alternately disposed retorts and tuyère rows, of fuel supporting means disposed at the lower ends of said retorts and lying between said tuyère rows, an ash pocket disposed at one end of said stoker having a front wall, one or more fluid conducting tubes mounted in cooling relation with the tuyères of each of said rows, said tubes extending downwardly and forming a portion of the front wall of said ash pocket, one or more fluid conducting tubes disposed in cooling relation with said fuel supporting means, a boiler, means operatively connecting said tubes to said boiler, and a booster pump for feeding fluid under pressure from said boiler to said tubes.
13. In an underfeed stoker, comprising in combination alternately disposed retorts and tuyère rows, dead plates disposed at the lower end of said retorts, an ash pocket disposed at one end of said stoker having a front wall, one or more fluid conducting tubes mounted in cooling relation with the tuyères of each of said rows, said tubes extending downwardly and forming a portion of the front wall of said ash pocket, one or more fluid conducting tubes disposed in cooling relation with said dead plates, a boiler, means operatively connecting said tubes to said boiler, and a booster pump for feeding fluid under pressure from said boiler to said tubes.
14. An underfeed stoker, comprising alternately disposed tuyère rows and retorts, fuel supporting means disposed at the lower ends of said retorts and lying between said tuyère rows, one or more fluid conducting tubes mounted above said tuyères and in spaced relation therewith, and one or more fluid conducting tubes disposed in cooling relation with said fuel supporting means.
15. In a furnace, the combination of a stoker, comprising alternately disposed retorts and tuyère rows, substantially horizontally disposed fuel supporting means provided at the lower end of each of said retorts, means comprising one or more tubes disposed longitudinally of and in cooling relation with said fuel supporting means, headers connecting the opposite ends of said tubes, means comprising one or more tubes extending from one of said headers and disposed in cooling relation with said tuyères, and means for supplying fluid to one of said headers.

JOSEPH S. BENNETT. 60
